UNITED STATES PATENT OFFICE.

GEORGE JOSEPH THOMAS, OF SOUTH BEND, INDIANA, ASSIGNOR TO BENDIX BRAKE COMPANY, OF CHICAGO, ILLINOIS, A CORPORATION OF ILLINOIS.

BAND BRAKE.

Application filed May 2, 1925. Serial No. 27,375.

This invention relates to brakes, and is illustrated as embodied in an automobile brake. An object of the invention is to provide an inexpensive construction, by using a band instead of formed shoes, while guarding against the tendency of a flexible band to lock itself, by making the band of relatively heavy material in a plurality of sections which may be regarded as semi-flexible shoes.

10 Important features of the invention relate to anchoring two of these sections at adjacent ends with the anchor of each between the ends of the other, to give the effect of overlapping the shoes, and to pivotally connecting two or 15 more sections, so that they may successfully be used when extended beyond 180 degrees.

These and other objects and features of the invention, including various novel combinations of parts and desirable particular 20 constructions, will be apparent from the following description of one illustrative embodiment shown in the accompanying drawings, in which:

Fig. 1 is a vertical section through the brake 25 just inside the wheel, showing the band in side elevation;

Fig. 2 is a bottom view of one of the cam-engaging ends of the band;

Fig. 3 is an inside plan view of the anchored 30 end of the center section of the band; and

Fig. 4 is an inside plan view of the pivoted end of one of the end sections of the band.

In the arrangement selected for illustration, the invention comprises a drum 10, with 35 in which is an expandable band in three sections 12, 14, and 16. Sections 12 and 16 are identical and interchangeable.

Each of the sections 12 and 16 has its free 40 end turned radially and supported by a pair of stampings or brackets 18 (Fig. 2), the radial ends of the sections engaging a double cam 20. Stampings 18 may be made with slotted openings 22 for stationary posts supporting a plate crossing the end of the cam

45 20, and confining the ends of the band sections laterally (see Patent No. 1,604,894, granted October 26, 1926, to Bendix Brake Company on an application filed by A. Y. Dodge).

At the other end of each shoe 12 and 16 is 50 secured a stamping bent to provide a pair of arms 24, shown as having tubular projections 26 sleeved upon an anchor 28, for section 12, or upon a pivot 30 connecting section 16 to a U-shaped stamping 32 secured to section 14.

55 Section 14 has its ends bent together at 34

(Fig. 3) and pivoted on an anchor 36 passing freely through a relatively large opening 38.

A spring 40 urges sections 12 and 16 away from the drum, and an auxiliary spring 42 guards against dragging of section 14 by insuring that it does not engage the drum until spring 42 is overcome by circumferential movement of section 16 due to the friction of the drum.

While one illustrative embodiment has been 65 described in detail, it is not my intention to limit the scope of the invention to that particular embodiment, or otherwise than by the terms of the appended claims.

I claim:

1. A brake comprising, in combination, a drum, a friction band adjacent the drum formed in a plurality of flexible sections, means for anchoring two of the sections at adjacent ends with the end of each anchored 70 between the ends of the other, and means forcing the ends of the band in opposite directions for forcing the sections against the drum.

2. A brake comprising, in combination, a 80 drum, a friction band adjacent the drum formed in a plurality of flexible sections, the end of one section being anchored and being narrowed adjacent the anchor, the end of the adjacent section having a pair of arms 85 straddling the narrowed part of the other and anchored between the ends of the other, and means engaging the ends of the band for forcing the sections against the drum.

3. A brake comprising, in combination, a 90 drum, a support at the open side of the drum, an expandable friction band in a plurality of flexible sections arranged within the drum, a pair of anchors for adjacent ends of said sections carried by the support, the anchor 95 of each section being between the ends of the other section, and means acting on the ends of the band for expanding the band against the drum.

4. A brake comprising, in combination, a 100 drum, a flat friction band within the drum, the band being in a plurality of flexible sections, means for anchoring adjacent ends of two of said sections, a pivot connecting a third section to one of the anchored sections, and means for expanding the band against the drum.

5. A brake comprising, in combination, a 105 drum, a flat friction band within the drum, the band being in a plurality of flexible sec- 110

tions, means for anchoring adjacent ends of two of said sections, the anchor for each section being between the ends of the other section.

5 6. A flat friction band section having its sides bent together adjacent one end to form a radial part, said part being constructed and arranged to be pivotally anchored.

7. A flat friction band section having its

sides bent together adjacent one end to form 10 a radial part, said part being perforated to receive an anchor pivot.

8. A friction band section having secured at its end a stamping formed with parallel arms arranged to be pivoted on an anchor.

15 In testimony whereof I have hereunto signed my name.

GEORGE JOSEPH THOMAS.
